UNITED STATES PATENT OFFICE.

JOHN P. STEEN AND WARREN W. ORAM, OF RUTHTON, MINNESOTA; SAID STEEN
ASSIGNOR OF HIS INTEREST TO MARCUS BLEGAN, OF RUTHTON, MINNESOTA.

POWDER PUFF.

Application filed December 2, 1921, Serial No. 519,504. Renewed October 2, 1922. Serial No. 591,985.

To all whom it may concern:

Be it known that we, JOHN P. STEEN and WARREN W. ORAM, citizens of the United States, residing at Ruthton, in the county 5 of Pipestone and State of Minnesota, have invented new and useful Improvements in Powder Puffs, of which the following is a specification.

Our present invention has reference to 10 powder puffs.

Our object is to produce a powder puff that includes in the construction thereof a powder receptacle or reservoir which is of an elastic or yieldable nature whereby, when 15 pressure is applied upon the rear or back of the puff, powder will be ejected from the receptacle through apertures between the fluffy outer face of the puff and the receptacle.

20 A further object is to produce a powder puff that includes a reservoir for the powder having means whereby the same can be readily filled when empty and also provided with apertured ports which communicate with the fluffy outer or active face of the puff, said receptacle being of a nature whereby pressure thereagainst, or rather pressure delivered thereon by contact with the rear face of the puff will cause the 25 powder to be ejected therefrom in desired quantities, the said receptacle being also of a nature whereby the powder will not accidentally be forced therefrom.

The foregoing, and other objects which 30 will appear as the nature of the invention is better understood, may be accomplished by a construction, combination and operative association of parts, such as is disclosed by the drawings which accompany and which 35 form part of this specification.

40 In the drawings:—

Figure 1 is a front elevation of a powder puff in accordance with this invention.

Figure 2 is a rear elevation thereof.

45 Figure 3 is a sectional view on the line 3—3 of Figure 1.

Figure 4 is a sectional view on the line 4—4 of Figure 3.

50 Figure 5 is a sectional view, approximately similar to Figure 3, but illustrating a slight modification.

The body of our improved powder puff may be considered similar to that of the ordinary construction, the same being round 55 in plan, and in the present instance com-

prises two members which are stitched or otherwise secured together to form the front or face 1 and the rear or back 2. Preferably the back has attached thereto a strap 3 for the convenience in operation by the user.

The body of the device is preferably constructed of fabric, the front 1 having a fleecy surface.

Between the front 1 and back 2 we arrange the reservoir or powder receptacle 4. The receptacle in the preferred embodiment of the improvement is in the nature of a rubber tube. The tube is preferably widened from its outer to its inner end, its said inner end being stitched to the front or the back or both of these members. The outer end of the tube projects through the stitching that connects the front and back, said reduced end having an outwardly projected metal neck portion 6. This neck is threaded and is designed to be engaged by a threaded cap 7. The tube has its side in contacting engagement with the face 1 of the puff secured thereto by any desired number of 80 comparatively small eye members 8, the said eyes being flanged upon both their inner and outer faces, the inner flanges, of course, contacting with the inner side of the receptacle, and the outer flanges contacting 85 with the fabric body of the facing 1.

If desired, however, and as illustrated in Figure 5 of the drawings, the receptacle may be provided with integrally formed teats 9 that pass through openings in the fabric body of the facing 1 and that are secured on the facing by a cement or by any other desired means. It is to be understood that the outer flanged ends of the teats or of the eyes are normally almost 90 entirely concealed by the fleecy surface 10 on the facing 1. It will be apparent that because of its elastic nature, a slight pressure upon the back 2 will cause a partial compression of the receptacle which will 95 force powder through the openings between the said receptacles and the facing 1.

With our improvement, the powder puff may be used for a comparatively long period of time without requiring the refilling of the receptacle. While we have referred to the receptacle as constructed of rubber, it is, of course, to be understood that the same may be constructed of other yieldable material, and also that the mouth of 110

the receptacle and the screw cap therefor are not necessarily constructed of metal as any other desired material may be employed. Also, if desired, the cap may be dispensed with and the mouth may be closed by a cork, cap, valve or any other desired means.

10 The reservoir is not necessarily in the form of a tube nor of an elastic nature, as the neck of the reservoir is of sufficient size to receive therethrough the powder when the reservoir is compressed. Also it is not a requirement that the reservoir be stitched or otherwise connected to either 15 the front or back of the puff as the eyelet will hold the reservoir on the face of the puff.

Having described the invention we claim:—

- 20 1. As a new article of manufacture, a powder puff comprising a back and a front which are connected together, a compressible reservoir between the front and back having a neck portion extending through 25 the edge of the puff, a closure for the neck, and ports establishing a communication between the outer face of the puff and the receptacle.

2. As a new article of manufacture, a powder puff comprising a fabric front and a fabric back which have their edges stitched or otherwise connected, and a strap on the back, the front having a fleecy facing, a compressible powder receptacle between the front and back having a neck portion extending through the edge of the puff, a stopper closing the neck, and means between the outer side of the receptacle and the front of the puff connecting these members together and establishing communicating ports therebetween.

3. As a new article of manufacture, a powder puff comprising an inner elastic powder container and an outer cover for the container having a fleecy surface, said container having a neck portion which extends through the cover, means between the side of the container and side of the cover connecting these members and establishing communicating ports therebetween, and means for closing the open neck portion of the puff to seal the same.

In testimony whereof we affix our signatures.

JOHN P. STEEN.
WARREN W. ORAM.
